UNITED STATES PATENT OFFICE.

MORTEN CHRISTOPHERSEN, OF BROOKLYN, NEW YORK.

FREIGHT-CAR.

1,333,464.

Specification of Letters Patent.

Patented Mar. 9, 1920.

Application filed October 11, 1919. Serial No. 329,959.

To all whom it may concern:

Be it known that I, MORTEN CHRISTOPHERSEN, a citizen of the United States, and a resident of the city of New York, borough

5 of Brooklyn, in the county of Kings and State of New York, have invented a new and Improved Freight-Car, of which the following is a full, clear, and exact description.

10 This invention relates to improvements in freight cars, an object of the invention being to provide a car of the box car type having a movable roof which can be hinged to either side of the car so as to expose the 15 load and permit the same to be removed by means of a derrick or other suitable mechanism through the top of the car.

It is a difficult matter with some materials to properly load and unload a box car 20 through the opening provided by a sliding door at the side and even where it is possible the work is slow and tedious. By providing a roof which can be moved out of the way, the operation of loading and unloading 25 can be greatly expedited.

The main object therefore of my invention is to provide a box car with a movable roof and improved means for mounting the roof and operating the same to hinge the 30 roof into either side of the car as may be most convenient for the operation.

With these and other objects in view the invention consists in certain novel features of construction, and combinations and arrangements of parts, as will be more fully hereinafter described and pointed out in the claims.

In the accompanying drawings—

40 Figure 1 is a view in side elevation; Fig. 2 is a view in end elevation;

Fig. 3 is a view in transverse section on the line 3—3 of Fig. 1;

Fig. 4 is an enlarged fragmentary view;

Fig. 5 is a view in section on the line 45 5—5 of Fig. 4; and

Fig. 6 is a view in section on the line 6—6 of Fig. 2.

1 represents the body of my improved car which is of the box type and 2 is the roof 50 which is made separate from the body of the car and is connected to the body at both sides by similar mechanism and hence the description of one of such mechanisms will apply alike to both.

55 It is, of course, to be understood that when the roof is in closed position, it will

be watertight and that the roof and the body will conform to the requirements of the railroads and will be standard in all respects.

60 The roof 2 at each side is provided with a series of brackets 3 fixed thereto and having integral perforated lugs 4 which are normally positioned between the perforated lugs 5 of bifurcated brackets 6 fixed to the 65 side of the car body. Below these brackets 6 longitudinally movable bars 7 are located and are supported by pins 8 projected through longitudinal slots 9 in the bars 7 and secured in the car body 1 so as 70 to permit the necessary longitudinal movement of the bars.

75 The bars 7 are provided with brackets 10 carrying horizontal pins 11 which are normally positioned in the perforated lugs 4 and 5 serving as locking pins to securely hold the roof on the body. When the bar 7 is moved to one extreme position, the pins 11 will be withdrawn from the perforated lugs sufficiently to free the lugs 4 and allow 80 the roof to be elevated.

It is, of course, to be understood that only one of these bars 7 will be operated at a time so that while the roof is freed at one side, the pins 11 at the other side hold the 85 roof and operate as hinge pins to allow the roof to be swung to an open position, as indicated in Fig. 2.

90 The body 1 is provided with the ordinary sliding doors 12 at the sides which are locked in closed position by means of hasps 13 positioned over the ordinary keeper 14 and held by a locking pin 15. A convenient means for moving the bar 7 is to provide a pivoted lever 16 connected by a link 17 95 with the bar 7 and provide a hasp 18 at the free end of this lever 16 which may be also positioned over the keeper 14 and locked by means of the same pin 15 so that a single seal will operate to seal the door and lock 100 the roof against unauthorized movement.

105 The roof 2 at both ends is provided with normally vertical pivoted rods 19, these rods being pivotally secured to the roof and movable in guide brackets 20 on the ends of the car, said guide brackets having rotary movement to accommodate the varying angular positions the rods assume in operation. Pulleys 21 are supported at the lower ends of the rods 19 and guide casings 23 are 110 secured to the ends of the car body and normally house the lower ends of the rods

19 and the pulleys to prevent possibility of accidental or unauthorized movement of the rods when the roof is in its closed position, and to guide the lower end of the rod into 5 the casing flared wings 24 are provided on the casing, as shown clearly in Fig. 2.

A shaft 22 is supported longitudinally in the bottom of the car body adjacent one side of the body and is provided at its ends 10 outside of the ends of the car with drums 25. Cables 26, at one end, fixed to and wound upon the drums 25, are passed over pulleys 27 supported by brackets 28 at the upper portion of the car ends, are then 15 passed downwardly and around the pulleys 21 and then passed upwardly and are secured to eye brackets 29 substantially in the same horizontal plane with the pulleys 27.

A worm wheel 30 is secured on the shaft 20 22 at one end of the car and is driven by means of a worm 31 on a short transversely positioned shaft 32 which projects to one side of the car body and is provided with a crank arm 33 to turn the same. This crank 25 arm is preferably so constructed as to permit its hinged movement to allow the same to be locked against the side of the car with the handle 34 in a recess 35 and held in such position by means of a pivoted covering 30 plate 36 so as to prevent the possibility of the handle becoming broken in the ordinary use of the car. The worm 31 is preferably mounted in an oil case 37 so as to insure a free turning movement at all times. In 35 order to permit the brake wheel 38 to be moved out of the way of the roof, the brake shaft 39 is made of two sections hinged together, as shown at 40, and a sliding sleeve 41 is normally positioned over the hinged 40 connection to hold the shaft sections in alinement, but when it is desired to operate the car roof, this sleeve can be elevated and the upper section of the brake shaft swung outwardly to the dotted line position shown 45 in Fig. 1.

The operation is as follows: The bar 7 at one side of the car is moved longitudinally to move the pins 11 out of the perforated lugs 4 on one side of the car, which would be 50 the dotted line position of Fig. 1. The crank handle 33 is then operated and, through the medium of the worm 31 and worm wheel 30, the shaft 22 is revolved to turn the drums 25 on the ends of the shaft and wind the 55 cables 26 thereon. This winding of the cables causes an upward push to be had upon the rods 19 to move the roof to open position and the roof may be opened as far as desired to give free access to the load in the 60 car.

To lower the roof it is simply necessary to turn the crank in the opposite direction allowing the roof to be slowly lowered into closed position, and when closed, the bar 7 65 is again operated to move the pins 11 into

the lugs 4 and secure the roof in such position.

Various slight changes may be made in the general form and arrangement of parts described without departing from the invention, and hence I do not limit myself to the precise details set forth but consider myself at liberty to make such changes and alterations as fairly fall within the spirit and scope of the appended claims. 75

I claim:

1. A car, comprising a body, a roof comprising a single member covering the body, separable hinge members connecting the roof at both sides with the car, and means 80 on the ends of the body for swinging the roof on either of said hinge members.

2. A car, comprising a body, a roof, separable hinge members connecting the roof at both sides with the car, a lever operating 85 the separable hinge members, and means for securing the lever against movement.

3. A car, comprising a body, a roof comprising a single member covering the body, separable hinge members connecting the 90 roof at both sides with the car, pivoted rods at the ends of the roof, pulleys on the rods, cables engaging the pulleys, and means for operating the cables to elevate the roof.

4. A car, comprising a body, a roof comprising a single member covering the body, separable hinge members connecting the roof at both sides with the car, a shaft mounted in the car, drums on the ends of the shaft, a worm wheel on the shaft, a 100 worm shaft, a worm on the worm shaft engaging the worm wheel, means for turning the worm shaft, and means operated by the drums for moving the roof. 95

5. A freight car, comprising a body, a 105 roof comprising a single member covering the body, separable means hingedly connecting both sides of the roof with the body, and means on both ends of the body for elevating the roof. 110

6. A freight car, comprising a body, a roof comprising a single member covering the body, separable means hingedly connecting both sides of the roof with the body, means at both ends of the body for elevating the roof, a shaft operating both of said 115 means, a worm wheel on the shaft, a worm meshing with the worm wheel, and means for turning the worm.

7. A freight car, comprising a body, a 120 roof on the body, perforated lugs on both sides of the roof, perforated lugs on the body, a sliding bar, and pins carried by the bar and movable into and out of said perforated lugs. 125

8. A freight car, comprising a body, a roof on the body, perforated lugs on both sides of the roof, perforated lugs on the body, a sliding bar, pins carried by the bar and movable into and out of said perforated 130

lugs, levers hinged to the sides of the car, and links connecting the levers and the bars.

9. A freight car, comprising a body, a roof hingedly and separably connected to both sides of the car, depending rods pivotally connected to the roof at its ends, pulleys carried by said rods, brackets secured to the ends of the car at opposite sides of the rods, a pulley on one of said brackets at each end of the car, drums at the ends of the car, cables secured to the other brackets passed around the pulleys on the rods, then over the pulleys on the brackets, and then secured to the drums, and means for turning 15 the drums.

10. A freight car, comprising a body, a roof hingedly and separably connected to both sides of the car, depending rods pivotally connected to the roof at its ends, pulleys carried by said rods, brackets secured to the ends of the car at opposite sides of the rods, a pulley on one of said brackets, drums at the ends of the car, a cable secured to one of said brackets passed around 20

the pulley on the rod, then over the pulley 25 on the bracket, and then secured to one of the drums, means for turning the drums, and casings secured to the ends of the car and receiving the lower ends of said rods therein when the latter are in their lowered 30 position.

11. A freight car, comprising a body, a roof hingedly and separably connected to both sides of the car, depending rods pivotally connected to the roof at its ends, pulleys carried by said rods, brackets secured to the ends of the car at opposite sides of the rods, a pulley on one of said brackets, drums at the ends of the car, a cable secured to one of said brackets passed around 35 the pulley on the rod, then over the pulley on the bracket, and then secured to one of the drums, means for turning the drums, and guide sleeves receiving said rods, said guide sleeves connected to the ends of the 40 car and having rotary movement.

MORTEN CHRISTOPHERSEN.
